Primary Examiner — Jennifer Rivard(74) *Attorney, Agent, or Firm* — John M. Lipchitz**CLAIM**

The ornamental design for a shaving razor handle, as shown and described.

DESCRIPTION

FIG. 1 is a first perspective view of a design of a shaving razor handle showing our new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof; and,

FIG. 8 is a bottom perspective view thereof.

The broken lines illustrate portions of the shaving razor handle and form no part of the claimed design.
